UNITED STATES PATENT OFFICE.

MOÏS H. AVRAM, OF NEW YORK, N. Y., ASSIGNOR TO THE AUTO-PROCESS SHOPS, OF NEW YORK, N. Y., A CORPORATION OF NEW YORK.

MACHINE FOR MAKING CIGARETTE PAPERS, TUBES, AND THE LIKE.

992,535.

Specification of Letters Patent. Patented May 16, 1911.

Application filed July 14, 1908. Serial No. 443,445.

To all whom it may concern:

Be it known that I, Moïs H. Avram, a citizen of the United States, residing at New York, county and State of New York, have 5 invented certain new and useful Improvements in Machines for Making Cigarette Papers, Tubes, and the Like, of which the following is a full, clear, and exact description.

10 My invention relates to a machine for making cigarette papers, and filled and unfilled cigarette tubes.

One of its objects is to form cigarette papers of uniform length.

15 It further has for its object to form said cigarette papers into cigarette tubes.

It further has for its object to produce a machine in which these cigarette tubes can be easily and expeditiously filled with tobacco.

20 It further has for its object to make cigarette papers and tubes one end of which shall be covered with a thin strip of cork or other tipping material so that the cigarette 25 made therewith shall be tipped.

It further has for its object to produce a machine in which the cigarettes shall be delivered in a definite position.

It further has for its object to produce a 30 tipped cigarette in which the joint of the tip shall be in line with the joint of the paper.

It further has for its object to produce a machine which shall apply the tipping substance continuously to a continuous paper 35 strip, the composite strip thus formed being subsequently cut into proper lengths or sections.

It further has for its object to produce a 40 machine in which the forming of the tube is begun before the section is severed from the continuous strip.

It further has for its object to produce a 45 machine in which the strip is properly guided and intermittently fed to the severing apparatus.

It further has for its object to produce a 50 simple and compact mechanism which shall be accurate and rapid in its operation and produce a uniform product.

55 The following is a description of an embodiment of my invention, reference being had to the accompanying drawings, in which,

Figure 1 is a front elevation with the front glue pot and glue rolls omitted. Fig.

2 is a side elevation looking from the left, 55 partially in section and with certain parts broken away for clearness. Fig. 3 is an end elevation of the body of the machine looking from the right, the driving gears and journals being removed. Fig. 4 is a detail view 60 showing cams and levers actuated thereby for actuating the mandrel inserting and extracting arms. Fig. 5 is a plan view of a portion of these levers and connections showing the mandrel extracting and inserting arms. Fig. 6 is a perspective view showing the mandrel inserting arm. Fig. 7 is a longitudinal section of the cylindrical former together with the mandrels and their guides. Fig. 7^a shows a detail of certain 70 intermittent gearing. Fig. 8 is a section on the line *a*—*a* of Fig. 7 (the paper being omitted) showing the means for causing the mandrel carriers to actuate certain folding fingers. Fig. 9 is a section on the line *b*—*b*, 75 Fig. 7, showing the forming drum and the folding fingers in various positions relatively to said drum and the forming grooves therein and their mandrels. Fig. 10 is a section on the line *c*—*c*, Fig. 7, showing the 80 folding fingers, front glue pot, glue carrier and feeding clamp, guide and severing members and other details. Fig. 11 is a front elevation of one severing member and the paper guide. Figs. 12, 13, 14 and 15 show 85 four positions of the feeding clamp, guide and severing members. Fig. 16 shows in side elevation the forming drum, feeding clamp and paper guide, together with cams and levers for actuating the clamp and 90 paper guide and also tube ejectors. Fig. 17 shows in diagrammatic perspective the relations of the paper roll and tip roll, and the composite strip formed by the union of the two. Fig. 18 shows in perspective a 95 complete tube.

Referring more particularly to the drawings, 1 is the base of the machine beneath which is an electric motor 2 driving a gear 3, to the shaft of which is also attached a 100 hand-wheel 4. Meshing with the gear 3 is a larger gear 5, which, by the yoke 6, can be thrown to the right or left so that the clutch recess 7 will engage or disengage the pin 8 in the shaft of the pinion 9. The 105 clutch recess 7 has one squared surface and one slanting surface with the result that when the hand-wheel 4 is turned in the

wrong direction the pin 8 is automatically disengaged by the clutch surface connected to the gear 5, thus preventing the accidental operation of the machine in the wrong direction. The gear-wheel 9 drives a gear-wheel 10, which is mounted upon the main shaft 11 of the machine. From this shaft the various parts of the machine are driven in the manner hereinafter described.

10 Supported above the base of the machine in suitable arms 12 is a roll of paper 13, which passes over guide-drums 14-15 to feed and pressure-rollers 17^a 18^a driven by gears 17 and 18. The gear 18, together with 15 its roller, is driven by the shaft 19 through the pulley 20 and belt 21, which passes over the pulley 22 on the main shaft 11.

Supported at a lower point, in the machine shown at a point below the base, is a 20 roll 23 of substance such as cork, gold paper or other like tissue, which it may be desired to apply to one edge of the paper passing from the roll 13 so as to be located at one 25 end of a cigarette-paper, tube or cigarette which may be made by the machine. The length of the roll 13 is made equal to the length of the paper or tube to be produced, the length of the tube being the full width of the paper upon the roll 13. The length 30 of the roll 23, *i. e.*, the width of the strip thereof, is made equal to the length of the tip desired. The strip from the roll 23 passes over guide-roll 24 and through guides 25-26 to a roll 27, being thus guided so that 35 one edge of the strip from the roll 23 coincides with one edge of the strip from the roll 13, as shown in Fig. 17. As the strip from the roll 23 passes from the guide 25, it is brought in contact with a glue-roll 28, 40 which is supplied with glue from the glue pot 29, the roll 28 being driven by a sprocket chain 30 from a sprocket upon the shaft of the gear 18. After passing the roll 27, the tipping strip, being then coated with glue, 45 comes in contact with the paper from the roll 13 and passing through the pressure rolls 17^a 18^a driven by the gears 17 and 18 is pressed so as to be firmly secured thereto, forming a composite strip 31. This 50 composite strip passes over a roller 32 to the feeding, severing and forming part of the machine.

In the embodiment shown, the feeding is 55 intermittent and since the rolls driven by the gears 17 and 18 move continuously, the slack in the composite strip 31 varies. In order to keep this strip at a uniform tension in spite of the variation in feed, I provide a floating roll or spool 33 which is supported 60 by the strip and moves up and down as the slack varies, thus securing the desired uniformity of tension.

The composite strip 31 is fed to a severing apparatus having two members 34-35, the 65 upper of which is pivoted at 36 and pressed

toward the lower member 35 by a flat-spring 37 so as to be held in close cutting engagement therewith. The outer end 34^a of the member 34 is connected to a link 38 which has at its lower end a pin 39 engaged by a cam 40 on the main shaft 11. As the main shaft is rotated, the member 34 is actuated by the cam 40, the cam being so timed that the cutting edge of the member 34 shall descend at the proper instant, its downward 75 spring movement being limited by the stop 34^b.

For the purpose of feeding the composite strip 31 to the severing device 34-35, I provide a reciprocating slide 41 which carries uprights 42 in which is pivotally mounted a jaw 43 adapted, in conjunction with the slide 41, to clamp and release the strip 31 so as to carry the strip 31 forward whenever the slide 41 moves forward. The clamp is 80 actuated by a rod 44 connected to a bell-crank lever 45, which at its other end has a roller 46 engaged by a proper cam 47 which lifts the clamp 43 at proper times so as to release the strip 31. A spring 48 connected to the bell-crank 45 at other times holds the jaw 43 in clamping engagement with the strip. The cam 47 is mounted on the shaft 49, which is driven by a gear 50 meshing with a gear 51 loosely mounted on the drum shaft 52 and in turn meshing with a gear 53 secured to the main shaft 11 (Figs. 1 and 3). The slide 41 is caused to reciprocate by a lever 54 pivoted at 55 and connected to the upright 42 by a link 56. The lower arm of 100 the lever 54 is connected by a rod 57 to a lever 58, the lever 58 being provided with a slot 59 so that the position of one end of the rod 57 can be shifted for the purpose of adjustment so as to vary the throw of the 105 slide 41 and thus vary the length fed to the severing device. A spring 60 is connected to the upper end of the lever 58 so as to hold it normally in retracted position and tend to retract the slide 41. The lever 58 carries an anti-friction roller 61 which bears against a cam 62 mounted upon the shaft 49 and therefore driven from the main shaft 11 synchronously with the cam 47. The cam 62, however, is differently shaped, the shape 115 being such as to give the slide 41 the desired movement at the desired time.

In order to properly guide the strip 31 between the severing members 34 and 35, a reciprocating guide 63 having inturned projections 64, on which the strip 31 rests, is provided. This guide is pivotally mounted at 65 on an arm depending from a slide 66 mounted in a stationary portion of the machine-frame and having connected thereto one end of the spring 67, the other end of which is connected to said stationary portion 68 so that the spring 67 tends to retract the slide 66, together with the arm 63 pivoted thereto. To the depending arm of the 120 125 130

slide 66 is also pivoted a latch 69 having a lug 70 engaging a pin 71 upon the slide for limiting its downward movement. This latch, when the slide 41 is in retracted position, as shown in Figs. 14 and 16, engages a projection 72 extending from one of the uprights carried by the slide 41. After such engagement has been made, a forward movement of the slide 41 carries the pawl 69 with it and consequently causes the guide 63 also to move forward with clamp 43. All these parts continue to move together until the forward end of the detent 69 engages the pin 73 as shown in Fig. 15. This engagement causes the detent 69 to rise until it escapes the projection 72, whereupon the guide 63 is retracted by the spring 67 to the position shown in Fig. 12. The clamp 43, however, continues to move forward, still carrying the paper until it has reached the position in which it is shown in Figs. 10 and 12. After it has reached this position, the cam 47 acting through the bell-crank 45 and rod 44 lifts the jaw 43, whereupon the cam 62, acting through the levers 58 and 54 retracts the jaw 43 and the slide 41 to the position shown in Fig. 13. The jaw 43 is still held open during the whole of the backward movement. The opening of the jaw 43 causes a projection 74, which in Figs. 10 and 12, is shown engaging the guide 63 so as to lift it slightly, to disengage said guide as shown in Fig. 13, thereby permitting the guide 63 to fall so that its heel engages the paper 31 so as to clamp it against the upper surface of the frame at 75, thereby holding its forward end during the interval in which it is released by the jaw 43. When the jaw 43 again engages the paper, the projection 74 again engages the guide 63 causing the guide to rise so as to no longer clamp the paper against the frame at 75.

Before the guide 63 in its forward movement reaches the severing members 34 and 35, these members have separated so that the guide 63 passes beneath them, as shown in Fig. 15. The end of the paper is thus properly introduced between the severing members and when so introduced can continuously be fed without difficulty by the action of the jaw 43. In the absence of means for holding the paper in a definite position and introducing it between the cutting members, there would be difficulty in causing the machine to handle paper of the thinness necessary for the purpose desired, particularly when pivoted severing members are employed. Before the severing members 34 and 35 come together the pin 73 causes the detent 69 to become disengaged with the result that the guide 63 is quickly drawn back out of the way of the severing members. By this means the paper can be accurately fed and brought between the severing members even though the opening is

small, thus preventing buckling and insuring certainty of action and uniformity in the lengths of the strips severed.

Figs. 10, 12, 13, 14 and 15 show five positions of the feeding clamp, guide and severing members. Fig. 10 shows the parts in their relation immediately after the retracting of the guide 63 and the full forward movement of the jaw 43, the paper being between the severing members 34-35. Fig. 12 shows these parts in the same relation except that the cutting edges of the severing members are about to engage. Fig. 13 shows the parts after the severing members have engaged and disengaged so that a section of paper is severed, and the jaw 43 has been raised and together with the slide 41 retracted, the paper being clamped at 75 by the guide 63. Fig. 14 shows these parts after the jaw 43 has been fully retracted so that the pawl 69 again engages the projections 72 and the jaw 43 has been caused to reengage the paper at a new point and raise the guide 63 so that the paper is no longer engaged at the point 75. Fig. 15 shows these parts after they have been moved forward so that the guide 63 extends beneath the cutting member 34 and the pawl 69 has engaged the pin 73 and is about to be thereby disengaged from the projection 72. The next position that the parts will assume is that shown in Fig. 10. By the means thus described, the paper and tipping material from the rolls 13 and 23 are secured together and cut into uniform lengths by the severing members 34 and 35.

In order to produce cigarette tubes, I provide a former and a mandrel coöperating therewith, said former having a recess over which the paper projects just prior to the time at which it is severed from the strip as shown in Fig. 10. In my present embodiment 76 is the former, the same being a cylinder mounted upon and driven by the drum shaft 52. This former has four recesses 77 equally spaced about its periphery. The shaft 52 by which it is rotated, has an intermittent motion, being driven by the intermittent gear 78, which is driven by the mutilated gear 79, the gear 79 having one-half of its circumference provided with gear teeth meshing with corresponding gear teeth on the gear 78, the other half of its circumference being cam-faced. The result is that during one-half of the revolution of the main shaft 11, while other parts of the mechanism driven thereby are rotating, the shaft 52, together with the drum 76 and other parts actuated solely thereby, remain stationary for the purpose hereinafter set forth.

Coacting with the former 76 are tubular mandrels 80, which are, by a movement transverse to their axes, brought into and out of line with the axes of the recesses 77. This is accomplished by a stationary cam 81

engaging anti-friction studs 82 carried by slides 83 moving in recesses 84 of a revolving frame 85 keyed to the drum-shaft 52 (see Figs. 2 and 7). These slides 83 carry 5 cylindrical rods or plungers 86 over which slide the hollow mandrels 80 (Fig. 7). The cam 81 is so timed that when any recess 77 approaches the severing members 34 35, the hollow mandrel 80 is elevated as shown in 10 Fig. 10 so as to pass over the end of the strip 31. As the recess moves a trifle closer, the cam 81 releases the slide 83 so that it is drawn downward by its spring 87 carrying its mandrel into the corresponding recess 77, thus folding and holding the paper as shown in Fig. 12. The severing member 15 34 then descends and severs the paper, which assumes the position shown in Fig. 13. Each slide 83 carries a projection 88, which partially surrounds the rod 86 and has depending 20 from it at its opposite end a rack 89. This projection also acts as an external guide for the mandrel. Each rack 89 engages a pinion 90 journaled in the former 76 and carrying at its inner end fingers 91 (see 25 Figs. 7, 8 and 9). The extremities of these fingers are caused to enter and withdraw from slots 92 in the drum 76 (see Figs. 1 and 9), these slots being formed by bridges 30 93 in one side of the recesses 77, (see Fig. 7). The purpose of these fingers is to clasp the paper and fold it over as the mandrels descend into their respective recesses 77. Since the mandrels and their respective 35 racks 89 move synchronously, the fingers 91 being driven by the racks 89 will reach the proper position so as to fold the paper over whenever any mandrel is seated in its slot 77. The position of the fingers 91 before the 40 mandrel drops is shown at the upper side of Fig. 9. The position after the mandrel drops is shown at the right of Fig. 9, the mandrel being in the bottom of the slot and the fingers being in engagement therewith. 45 The mandrel and the fingers remain in this position until the slot reaches substantially its lowermost position at or about which time the cam 81 begins to force the lowermost slide, together with its mandrel, downward, resulting in the withdrawing of the 50 corresponding fingers 91, which releases the tube so that it can drop out or be removed, when its mandrel 80 is fully withdrawn from the recess by a longitudinal movement 55 hereinafter described. Just after a slot 77 has reached its lowermost position and after the mandrel has been withdrawn, an ejector 94 actuated by a cam groove 95 in which roller pin 96, carried by the ejectors travel, 60 forcibly ejects the tube from the recess. The mandrels 80 have roller studs 97 connected thereto, which project through slots 97' in the projections 88, being guided and positioned thereby. These roller studs 97, 65 when the mandrels reach their lowermost

position, are engaged by retracting members 98 carried by parallel lever arms 99—100, the former being rigidly connected to a bevel gear 101 and the latter being pivoted to the frame at 102, so as to cause the member 98 70 to be maintained transverse to the axis of the mandrel which it is withdrawing. The bevel gear 101 is driven by a bevel gear 103 which is mounted on a shaft 104, on which is mounted the arm 105 pivoted at its upper 75 end to an inserting member 106. This inserting member is connected to the parallel arm 107 so that it is maintained parallel to the axis of the mandrel which is inserted thereby. This insertion member 106 engages a pin 97 on one of the mandrels when the mandrel has reached the position shown at the left hand side of Fig. 9 (see Fig. 5). The shaft 104 on which the bevel gear 103 is mounted has an arm 108, to which is connected a link 109, which is driven by a lever 110 pivoted at 111. The lower end of the lever 111 has connected to it a link 112 which is connected to a lever 113 pivoted at 113^a and normally retracted by a spring 113^b. This lever 113 carries an anti-friction roller 114 which engages a cam 115. This cam 115 is mounted on a shaft 116 which carries a bevel gear 117 engaging a bevel gear 118 mounted on the main shaft. The 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 glue pot. The yoke 130, together with its rollers 126 and 127 tends to fall down by gravity and when in its lowermost position the roller 126 makes contact with the edge of the blade 119. Connected to the rotating drum is a cam surface 132 which determines the position of the roller 126, permitting it to descend at the proper time so as to touch the edge of the blade 119 and cover it with 10 glue. This cam surface engages a friction surface on the shaft of the roller 126, causing it to rotate and thus causing the rollers 127 and 128 to also rotate so that they are all kept properly coated with glue.

15 After the glue has been applied, the former 76 moves and a stationary wiper 133 secured to the frame at 134 (Figs. 2 and 10) wipes the glued edge over on to the unglued edge of the section. A brush 135, 20 mounted on the frame, gives the glued edge an additional and more perfect wipe as the tube is carried by, thus insuring the production of a perfect joint.

25 The course of the paper and tipping strip, and the composite strip formed thereby, is shown diagrammatically in Fig. 17 showing the path which they take.

30 Fig. 18 shows a complete tube, the edges of the paper and the edges of the tipping strip being connected together in the same longitudinal line.

35 The operation of the machine is as follows: After the paper 13 and the tipping strip 23 have been placed in position and passed over and between the proper rollers until they reach the clamping jaw 43 and guide 63, the machine being manipulated during this process by the hand-wheel 4, the electric motor is started. The clamping jaw 40 43, together with the slide 41, carries the paper forward beneath the severing members 34-35 as shown in Fig. 15. The guide 63 is then released and withdrawn by the spring 67, the jaw 43 continuing its forward 45 motion until the strip has reached the position shown in Fig. 10. As the tipping strip passes the roller 28, it becomes coated with glue. It is then brought in contact with the paper strip and passes between the rollers 50 17^a-18^a where the pressure causes the two to adhere. It is then fed by the jaw 43 and guide 63 to the severing device, which cuts it off in sections of equal length. When the machine is used for making cigarettes or

55 cigarette tubes, the uppermost mandrel 80 falls into its recess 77 just before the strip section is severed, as shown in Fig. 12, after which the uppermost blade 34 descends so as to sever a section of the strip. The jaw 43 is then moved backward, the guide meanwhile clamping the forward end of the paper until the jaw 43 has reengaged the same. After the strip has been severed, the glue conveyer 119, which has been coated 60 with glue, is moved upward so as to make

contact with one edge of the severed section as shown in Fig. 14, after which a movement of the former 76 carries the strip beneath the stationary wiper 133 and the brush 135, securing the two edges together. When 70 the former has moved so that the tube thus formed has reached its lowermost position, the mandrel is withdrawn by the withdrawing member 98. The mandrel then rises slightly from the groove under the action of the cam 75 81, the corresponding fingers 91 being retracted so that the tube is free to fall or be forced out by the corresponding ejector 94. When the withdrawn mandrel reaches the position shown at the left of Fig. 9, the inserting member 106 engages the same and forces it in a direction parallel to its axis back to its initial position (see Fig. 5), in which position it remains until it has reached the position shown at the upper portion 85 of Figs. 7 and 9 except for the fact that it has been forced farther outward by a movement transverse to its axis due to the cam 81. This operation is repeated as each mandrel and its corresponding recess travels 90 around the circumference, resulting in the making of four complete tubes for each revolution of the former 76, the parts being properly timed by the means before described so as to work together to produce 95 the desired result.

It is to be noted that the mandrels 80 are hollow so that they can be filled with tobacco, if desired, by any suitable means, and that when the mandrels are withdrawn by 100 the withdrawing members 98, the rods 86 act as ejectors for the contents of the mandrels 80 so that the contents of these mandrels will be left within the tubes. Any suitable automatic means for filling the mandrels 80 with tobacco can be used. It is to be noted that on delivering the completed tubes, the pasted edges will always be on the bottom and on account of this uniformity of delivery position, can be arranged 105 with uniformity in the receptacle into which they may be delivered.

110 My invention permits of embodiment in various modified forms in which well known mechanical equivalents can be substituted for some of the particular parts shown and described.

115 What I claim is:

1. In a machine for making tubes, the combination of means for supplying a continuous strip, means for severing said strip into equal sections, a former having a recess for receiving said sections one at a time, a mandrel co-operating with said recess, means for moving said mandrel transversely to its axis into said recess so as to hold the section therein, means for folding the overlapping edges of said section against the mandrel to form a tube, means for withdrawing said mandrel by a movement parallel to its axis, 120 125 130

said mandrel being tubular, and a rod over which said mandrel passes when being withdrawn from said recess.

2. In a machine for making tubes, the combination of means for supplying a continuous strip, means for severing said strip into equal sections, a former having a recess for receiving said sections one at a time, a tubular mandrel coöoperating with said recess, means for moving said mandrel transversely to its axis into said recess so as to hold the section therein, said moving means including a rod over which the mandrel passes when being withdrawn from the recess, means for folding the overlapping edges of said section against the mandrel to form a tube, means for withdrawing said mandrel by a movement parallel to its axis, a finger pivoted to said former, and adapted to 15 to clasp said mandrel when the mandrel is moved transversely into said recess.

3. In a machine for making tubes, the combination of a revolving former having a plurality of recesses therein parallel with, but eccentric to the axis of rotation, a plurality of hollow mandrels coacting with said recesses, means for giving said mandrels a reciprocating motion to and from said axis of revolution, means for giving said mandrels a reciprocating motion parallel to said axis, rods rotating with said mandrels and over which said mandrels pass when being withdrawn from said recesses by the movement parallel to said axis.

35. 4. The combination of means for supplying a strip, a severing means, a reciprocating device feeding said strip to said severing means, and a guide, said guide and feeding device moving synchronously when both are 40 moving forward but moving asynchronously during their return movements.

5. The combination of a reciprocating feeding clamp, a reciprocating guide, one of said member carrying a pawl and the other 45 a projection with which said pawl engages, means for moving said clamp forward when said pawl engages said projection, an abutment disengaging said pawl from said projection, and a spring retracting said guide 50 when said pawl is thus disengaged.

6. In a tube forming machine, the combination of a former having a recess, a mandrel for said recess adapted to hold a strip section therein, a glue pot, a roller supplied with glue therefrom, a movable glue carrier, and means for causing said carrier to contact alternately with said roller and one edge of said strip section.

7. In a tube forming machine, the combination of a former having a recess, a mandrel for said recess adapted to hold a strip section therein, a glue pot, a roller supplied with glue therefrom, a moving glue carrier, means for causing said carrier to contact 60 alternately with said roller and one edge

of said strip section, and a wiper, the mandrel and said wiper being relatively movable, said wiper bringing the two edges of the strip in contact after the application of the glue.

8. In a tube forming machine, the combination of a former having a recess, a mandrel for said recess adapted to hold a strip section therein, a glue pot, a roller supplied with glue therefrom, a moving transfer device and means for causing said transfer device to contact alternately with said roller and one edge of said strip section, said transfer device having a surface adapted to contact with and fold the other edge while 75 said strip section is within said former.

9. In a tube forming machine, means for forming strip sections, combined with a rotating former 76, fingers 91 within the same, slides 83 geared to said fingers, rods 86 carried by the slides and revolving with said former, but eccentric to its axis, hollow mandrels 80 slideable on said rods, a cam 81 adapted to move said slides and rods transversely, withdrawing and inserting members 98 and 106, and means for causing the edges of the strip sections to come together and adhere.

10. In a cigarette machine, the combination of a revolving former having a recess 95 in its periphery parallel to the axis of revolution, means for supplying a continuous web of paper thereto in a direction at right angles to the axis of said former, a mandrel, means for moving said mandrel transversely to its axis so as to force the paper into said recesses, a severing device, means for operating said severing device so as to cause it to sever said paper while held by said mandrel, means for folding the overlapping edges of the paper against the mandrel to form a tube, and means for moving said mandrel longitudinally so as to withdraw it from the tube thus formed, and to restore it to its original position.

11. In a cigarette machine, the combination of a revolving former having a recess in its periphery parallel to the axis of revolution, means for supplying a continuous web of paper thereto in a direction at right 115 angles to the axis of said former, a mandrel, means for moving said mandrel transversely to its axis so as to force the paper into said recesses, a severing device, means for operating said severing device so as to cause it to sever said paper while held by said mandrel, means for folding the overlapping edges of said paper against the mandrel to form a tube, and means for moving said mandrel longitudinally so as to withdraw it from 120 the tube thus formed, and to restore it to its original position, and means for removing the tube when completed from said former.

12. In a cigarette machine, the combina- 13

tion of a former having a plurality of recesses therein, a corresponding number of mandrels coöoperating with said recesses, means for supplying a continuous strip of paper by a movement transverse to the axis of said former, means for moving said mandrels transversely to their axes so as to enter said recesses and hold the paper therein, means for severing a strip section from said strip while held in one of said recesses by one of said mandrels, means for folding the overlapping edges of said paper against the mandrel to form a tube, and means for withdrawing said mandrels from the tube thus formed and returning them to their initial position.

13. In a cigarette machine, a revolving former having a plurality of recesses in its periphery, a corresponding number of tubular mandrels co-acting with said recesses and revolving synchronously therewith, a corresponding number of ejectors revolving with said mandrels and over which said tubular mandrels are adapted to slide, means for supplying strip sections to the recesses of said revolving former, means for moving said mandrels toward the axis of said former so as to hold the strip sections therein, means for folding the overlapping edges of said paper against the mandrel to form a tube, and means for moving said mandrels longitudinally so as to pass out of the tubes thus formed and over said ejectors and clamping fingers adapted to move toward the same when said mandrels are moving into said recesses by said transverse movement, and to move away from the same when said mandrels are moving transversely in the opposite direction.

14. In a cigarette machine, a revolving former having a plurality of recesses in its periphery, a corresponding number of tubular mandrels co-acting with said recesses and revolving synchronously therewith about the axis of said former, a corresponding number of ejectors revolving with said mandrels

and over which said tubular mandrels are adapted to slide, means for supplying strip sections to the recesses of said revolving former, means for moving said mandrels toward the axis of said former so as to hold 45 the strip sections therein, means for folding the overlapping edges of said paper against the mandrel to form a tube, means for moving said mandrels longitudinally so as to pass out of the tubes thus formed and over 50 said ejectors and clamping fingers adapted to move toward the same when said mandrels are moving into said recesses by said transverse movement, and to move away from the same when said mandrels are moving 55 transversely in the opposite direction.

15. In a cigarette machine, the combination of a revolving former, having a plurality of recesses therein parallel to its axis of revolution, a corresponding number of 60 mandrels revolving with said former and co-acting with said recesses, means for feeding tube sections beneath said mandrels and over said recesses one at a time in a direction at right angles to the axis of said former, 65 means for moving said mandrels transversely so as to enter said recesses, means for severing the tube sections one at a time while held within said recesses by said mandrels, means for folding the overlapping 70 edges of said sections against the mandrel thereby causing the edges of said tube sections to adhere together forming a complete tube, means for withdrawing said mandrels by a longitudinal movement and restoring 75 them to their initial position.
